(57) **CLAIM**

The ornamental design for an animal waste collecting apparatus, as shown and described.

DESCRIPTION

FIG. 1 is a top perspective view of the animal waste collecting apparatus of the instant invention;

FIG. 2 is a right view thereof;

FIG. 3 is a left view thereof;

FIG. 4 is a top view thereof;

FIG. 5 is a bottom view thereof;

FIG. 6 is a front view thereof;

FIG. 7 is a back view thereof;

FIG. 8 is another perspective view thereof; and,

FIG. 9 is an exploded view thereof.

The handle is shown broken away in the figures to indicate that a specific length of this portion of the animal waste collecting apparatus forms no part of the claimed design.

1 Claim, 9 Drawing Sheets
